REINFORCED I-BEAM

Maurice Lachman, New York, and Laurence S. Lachman, Forest Hills, N. Y., assignors to Structural Patents Corporation, New York, N. Y., a corporation of New Jersey

Application October 3, 1942, Serial No. 460,620

2 Claims. (Cl. 189—37)

The present invention relates to structural metal work generally and more particularly to reinforcement and consequent strengthening of beams which may be used either singly or in combination with other members, such as angles, plates and the like, to produce trusses, girders and analogous structures of varying characters and constructions suitable for use for a variety of purposes.

The principal object of the invention is the production of a reinforced beam, such as a conventional and standard rolled I-beam, or any other beam employing essentially a web and laterally or horizontally extending flanges integral therewith, by means of simple and inexpensive expedients adapted to very appreciably enhance its strength and render it effectively resistant to strains and stresses of whatever nature and capable of sustaining very heavy loads applied under compression.

A further object of the invention is the production of a beam of the character referred to which shall be so reinforced as to permit its employment in a size much smaller than ordinarily would be required and necessary for any predetermined construction or for its intended purpose.

A further object of the invention is the production of a structural member comprising a flanged web the normally unsupported flanges of which are so supported or reinforced as to enable the flanges per se to sustain heavy loads which normally would not be possible without danger of buckling, deflection or fracture.

A further object of the invention is the production of a beam comprising a flanged web so reinforced as to permit access to be readily had to its interior surface for cleaning purposes or for painting to obviate the formation of rust and consequent deterioration of the beam from corrosion.

Other and further objects and advantages of the invention will appear from the accompanying description, the invention consisting in the reinforced structural member or beam hereinafter more particularly described and then specified in the claims.

Referring in detail to the several figures of the accompanying drawing:

Fig. 1 is an enlarged perspective view of the structural beam of the invention.

Fig. 2 is a side elevation thereof.

Fig. 3 is a horizontal section on the line 3—3 of Fig. 2, and

Fig. 4 is a perspective view of the struts con-

stituting the strengthening and the supporting members.

Referring further to the several views of the drawing:

5 The web of an I-beam is indicated at 10 while the upper and lower flanges thereof which are integral with the web are indicated at 11 and 12 respectively. The I-beam is preferably, although not necessarily, a conventional and rolled I-beam, of standard size and construction. Such beams are employed for a variety of purposes and for various uses in structural metal work and are adapted especially to sustain loads that are applied under compression. Ordinarily, however, 10 the flanges of such beams are unsupported excepting centrally thereof as by the web 10 so that such flanges, especially the areas adjacent their sides or edges, are susceptible to deflection, bending or buckling if the applied loads are of excessive weight. To appreciably enhance the 15 strength of such beams, and to obviate the objections referred to, the opposed edges of the upper and lower flanges are rigidly connected together by rectilinear struts constituting latticed or reticulated strengthening and supporting members and forming openings therebetween of a size permitting access to be conveniently had to the interior surface of the I-beam for cleaning and painting purposes. Said struts in effect also 20 constitute supplemental webs spaced from the conventional web 10 whereby the flanges of the beam not only are supported centrally thereof but at their free ends as well. The resulting 25 structure, obviously, is one of great strength and rigidity.

For the strengthening and supporting struts it is preferred to employ conventional rolled channels because of their inherent strength and because they are standard in size and construction 30 and are easily procurable. Channels are also preferably employed for the reason that they provide a plurality of welding projections or points enabling them to be conveniently and rigidly welded to the edges of the opposed flanges. As an alternative, however, it will be understood 35 that in some cases rods, wires or plates may be conveniently utilized as the strengthening and supporting struts. The channels preferably are utilized in pairs, each channel of which crosses the other channel and is integrally connected thereto. The ends of both channels are then rigidly connected, preferably by welding, to the opposed edges of the flanges of the I-beam.

The web of the outer one of the aforesaid pairs 40 of channels is indicated at 18 while its flanges,

which are integral with the web, are indicated at 17. Said flanges 17 are provided with aligned right-angled slots 18 centrally thereof of a size permitting them to snugly receive the other or inner channel of the pair. The web of the inner channel is indicated at 13 while its flanges, which are integral therewith, are indicated at 14. Said flanges 14, at their ends, are preferably cut away to shorten the depths of the flanges and to form shoulders 15.

A pair of the aforesaid channels is assembled, one on the other, by reception of the inner channel within the slots 18 of the outer one and the members are then rigidly and integrally connected together in crossed relation by electrically spot welding, as by spot welds 19, the flange 13 to the flange 16 at their places of intersection. When so inter-connected, obviously, the channels lie at right angles to each other but the angle between them may be conveniently diminished or increased to vary the degree of inclination of the members to suit varying conditions and one's convenience by cutting the receiving slots 18 in alignment through the flanges 17 diagonally of the central axis of the channel and at any desired degree of inclination.

The edges of the flanges of the channels adjacent their ends are rigidly and integrally connected to the free edges of the opposed flanges 11 and 12 of the I-beam, preferably by employment of the pressure electric resistance welding process now well known in the art and by passing heating electric current through the opposed parts with the simultaneous application of pressure. The edges of the flanges of the channels provide with the edges of the flanges 11 and 12 sharply defined relatively small areas of contact admirably suited for the practice of that process thus minimizing the amount of electric current necessary and facilitating and expediting the welding operation. The shortening of the depth of the ends of the flanges 14 in the inner channel in each pair by the provision of the shoulders 15 is desirable to insure contact of the edges 17 of the outer channel with the edges of the flanges 11 and 12 when the intersecting channels are assembled on said flanges in welding position. Otherwise, such contact might not be practicable or possible without an undesirable bending of one of the interconnected crossing channels, as obviously, they do not lie in the same general plane. It will be noted, however, that the ends of the channels are electrically welded to the edges of the flanges 11 and 12 at two separated and distinct points which not only makes for rigidity and strength of the welded joints but acts to greatly resist any tendency to disconnection of the welded parts or movement of one with respect to the other. Any suitable construction of electric welding machine may be employed for practicing the electric welding process, which also obtains in the case of the spot welds 19 hereinbefore referred to.

As is manifest, the strengthening of a flanged web or analogous structural beam in the manner explained enables the flanges, which ordinarily are entirely unsupported except centrally thereof, to sustain very heavy loads. In the case of an I-beam, as an example, which is provided with flanges of appreciable width, such, for instance, as that shown in Figure 1, the merits and advantages of the invention will be obvious. In cases of this character, loads applied to the beam under compression may be applied with efficacy, is so desired, on a vertical neutral axis remote

from the vertical axis of the web without danger of deflection, buckling or fracture of the flanges. Any number of channels or pairs of channels or other strut members may be employed depending on varying conditions, and the distances between the strut members or pairs thereof may vary as well. In all cases, at least certain of the reinforcing strut members are shouldered at their ends for engagement with the flanges of

5 the beam, so that compressive forces acting on the beam flanges are transmitted through such end shoulders and are resisted by the strut flanges, which are themselves stiffened by the strut webs, without straining the welded or other type of connection by which the struts are fastened to the beam proper.

It will also be apparent that by means of the invention, structural beams will be found sufficient when made of appreciably less size and weight than ordinarily would be necessary for any given construction. This results in a great saving of material and expense. Still a further and important advantage of the invention lies in the fact that if through error or miscalculation a structure has been completed in which structural members comprising flanged webs, such as I-beams, have been employed but whose size and strength are insufficient to permit them to satisfactorily perform their proper and intended functions, they may often be conveniently and expeditiously reinforced in accordance with the invention described.

The invention claimed is:

1. A structural beam comprising a web, a flange 35 extending laterally in the same direction from each edge of the web to form therewith a channel shape, a plurality of reinforcing strut members bracing the free edges of said flanges, each of said strut members comprising a web and a 40 pair of flanges arranged in channel shape and extending at an oblique angle between the beam flanges and crossing a similar strut member at a zone intermediate its ends, all of the strut flanges extending toward the beam web and certain of them having their end portions cut away to form end shoulders engaging the beam flanges, and the flanges of the remainder of said strut members being cut out at said intermediate zone of each to provide a slot having shoulders 45 engaging the crossing strut member, means securing the webs of the strut members of each crossing pair together and means securing the flanges only of said strut members to the beam flanges, whereby compressive forces acting on the beam flanges are transmitted through said end shoulders and are resisted by said strut flanges, and whereby said strut webs are uncut and serve to stiffen said strut flanges.

2. A structural beam comprising a web, a flange 60 extending laterally in the same direction from each edge of the web to form therewith a channel shape, a plurality of reinforcing strut members bracing the free edges of said flanges, each of said strut members comprising a web and a pair 65 of flanges arranged in channel shape and extending at an oblique angle between the beam flanges and crossing a similar strut member at a zone intermediate its ends, all of the strut members extending toward the beam web and certain of them having their end portions cut away to form end shoulders engaging the beam flanges, and the flanges of the remainder of the strut members being cut out at said intermediate zone of each 70 to provide a slot having shoulders engaging the crossing strut member, a welded connection be-

tween each of said beam flanges and the flanges only of said strut members, and a welded connection between the webs of the strut members of each crossing pair, whereby said welded connections secure the strut members to each other and to the beam with the webs of the strut members spaced by the flanges thereof from the

5 flanges of the beam, and whereby compressive forces acting on the beam flanges are transmitted through said end shoulders and are resisted by said strut flanges, said strut webs being uncut and serving to stiffen said strut flanges.
